Primary Examiner — Selina Sikder(74) *Attorney, Agent, or Firm* — Price Heneveld LLP; Bradley D. Johnson(57) **CLAIM**

We claim the ornamental design for a control switch, as shown and described herein.

DESCRIPTION

FIG. 1 is a bottom first side perspective view of a control switch of the present disclosure;

FIG. 2 is a bottom second side perspective view of the control switch of FIG. 1;

FIG. 3 is a top plan view of the control switch of FIG. 1; FIG. 4 is a bottom plan view of the control switch of FIG. 1;

FIG. 5 is a first side elevational view of the control switch of FIG. 1;

FIG. 6 is a second side elevational view of the control switch of FIG. 1;

FIG. 7 is a rear elevational view of the control switch of FIG. 1; and,

FIG. 8 is a front elevational view of the control switch of FIG. 1.

The broken lines depict portions of the article that form no part of the claimed design.

1 Claim, 5 Drawing Sheets(56)
